William J. Flett, Drexel Hill, Pa., assignor to
Turnsignal Corporation, Philadelphia, Pa., a
corporation of New Jersey

Application June 10, 1953, Serial No. 25,427

Term of patent 7 years

(Cl. D48—32)

To all whom it may concern:

Be it known, that I, William J. Flett, a citizen of the United States of America, residing in Drexel Hill, Delaware County, Pennsylvania, have invented a new, original, and ornamental Design for a Cover Lens for Turn Signal Devices, of which the following is a specification, reference being had to the accompanying drawing, forming part thereof, in which:

Figure 1 is a rear elevational view of a cover lens for signal devices showing my new design;

Fig. 2 is a sectional view taken along line 2—2 of Fig. 1;

Fig. 3 is a front elevational view thereof; and
Fig. 4 is a side elevational view thereof.

I claim:

The ornamental design for a cover lens for turn signal devices, substantially as shown.

WILLIAM J. FLETT.
